(57) **CLAIM**

The ornamental design for a pipe cap for drain pipe outlet, as shown and described.

DESCRIPTION

FIG. 1 is a front top perspective view of a pipe cap for drain pipe outlet showing my new design.

FIG. 2 is a front elevation view of the pipe cap for drain pipe outlet as shown in FIG. 1 showing my new design.

FIG. 3 is a rear elevation view of the pipe cap for drain pipe outlet as shown in FIG. 1 showing my new design.

FIG. 4 is a left side elevation view of the pipe cap for drain pipe outlet as shown in FIG. 1 showing my new design.

FIG. 5 is a right side elevation view of the pipe cap for drain pipe outlet as shown in FIG. 1 showing my new design.

FIG. 6 is a top plan view of the pipe cap for drain pipe outlet as shown in FIG. 1 showing my new design.

FIG. 7 is a bottom plan view of the pipe cap for drain pipe outlet as shown in FIG. 1 showing my new design.

FIG. 8 is a front top perspective view of the pipe cap for drain pipe outlet as shown in FIG. 1 showing my new design and having a piece removed.

FIG. 9 is a front elevation view of the pipe cap for drain pipe outlet as shown in FIG. 8 showing my new design.

FIG. 10 is a rear elevation view of the pipe cap for drain pipe outlet as shown in FIG. 8 showing my new design.

FIG. 11 is a left side elevation view of the pipe cap for drain pipe outlet as shown in FIG. 8 showing my new design.

FIG. 12 is a right side elevation view of the pipe cap for drain pipe outlet as shown in FIG. 8 showing my new design.

FIG. 13 is a top plan view of the pipe cap for drain pipe outlet as shown in FIG. 8 showing my new design; and,

FIG. 14 is a bottom plan view of the pipe cap for drain pipe outlet as shown in FIG. 8 showing my new design.
